CARBURETOR

Fred A. Kommer, St. Louis, Mo., assignor to
 Carter Carburetor Corporation, St. Louis, Mo.,
 a corporation of Delaware

Application May 4, 1935, Serial No. 19,839

12 Claims. (Cl. 137—68)

This invention relates to carburetors for internal combustion engines, and more particularly to a new and improved pivot mounting for the float which controls the fuel intake valve for the constant level chamber.

In previous carburetor constructions the float has been mounted on a horizontal pin supported in the walls of the float chamber. This pin had to pass thru at least one wall in assembly and required a closure and, besides being comparatively expensive, permitted a possible fuel leakage, particularly after frequent removals and insertions of the pivot pin for the purpose of adjustment or replacement of other parts of the device.

It is an object of this invention to provide an improved float support arrangement of the above described character, having an economical construction, and facilitating assembly and access to parts for adjustment or replacement.

It is a further object of this invention to provide a novel and improved method of securely mounting a float lever pivot pin.

Other objects will appear from the following description and accompanying drawing, referring to which:

Figure 1 is a vertical sectional view of a carburetor embodying my invention.

Figure 2 is a plan view of the carburetor shown in Figure 1 with parts broken away for better disclosure.

Figure 3 is a sectional view taken on line 3—3 of Figure 1 in the direction of the arrows.

Figure 4 is a perspective view of the pivot retaining spring.

Figure 5 is a fragmentary view with parts removed for clearer disclosure.

The reference numeral 1 indicates the main body member of the carburetor having a combination air horn and constant level chamber cover 2 attached thereto by any suitable means such as screws 3. A mixture conduit is formed by air inlet 4, venturi 5, mixing chamber 6 and mixture outlet 7. The air inlet is controlled by the choke valve 8 which is pivotally mounted on shaft 9 and may be operated manually by means of lever 10 or by any suitable automatic or semi-automatic means. Throttle valve 11 pivotally mounted on shaft 12 and operated by suitable means thru lever 13 controls the mixture outlet.

A constant level chamber 14 is formed in the main body member of the carburetor and a boss 15 having the horizontal threaded passage 16 therethru is provided for threaded engagement 55 of inlet fitting 17. A threaded longitudinal pas-

sage 18 is provided at one end of the inlet fitting for conventional attachment of a fuel supply conduit and a concentric passage 19 at the opposite end of the fitting provides a guide for the flat sided body of the needle valve 20, passages 18 and 19 being connected by a smaller passage 22 forming valve seat shoulder 21.

Fuel is delivered to the constant level chamber from the main fuel supply tank by pump or gravity means and is admitted thereto thru the inlet fitting and a constant level of fuel, substantially as shown, is maintained within the constant level chamber by float 23 acting upon the needle valve 20 thru the float lever 24 which is rigidly attached to the float and pivotally mounted on float lever pin 25.

For the mounting of the float lever pin a pair of vertical grooves 26 are formed in opposite inner walls of the constant level chamber, and a float lever pin retainer 27 arranged for insertion in grooves 26 is provided for the purpose of confining the float lever pin to the lower end of the grooves, as indicated at 36, when the cover 2 is attached.

The construction and material of the float lever pin retainer 27 are preferably such as to permit at least some yieldability vertically and laterally, on account of the varying amount of compression of gasket 28 which may occur as the cover 2 is tightened down by screw 3 to effect a fuel tight seal, and also on account of the greater accuracy required and therefore more costly manufacture of a non-yieldable retainer. By using this yieldable construction, and by making the normal height of the member 27 slightly greater than the depth of the groove 26, I insure a snug but free operating fit for the pin 25. The retainer is preferably, of such width that the ends must be distorted inwardly in assembly so as to frictionally grip the inner walls of the grooves. This facilitates assembly where the carburetors are progressively assembled in a production line, particularly where the same operator does not assemble the float support mechanism and the bowl cover.

I prefer to use a low temper metal such as half hard brass or steel in the manufacture of the retainer, because of the lower cost and the ease with which it may be formed as compared with high temper metal. Sufficient yieldability, both horizontally and vertically, is obtained by the general U-shape construction of the retainer, as indicated in the drawing. The thickness and width of the stock are of some importance, as the use of material too thick or too wide will in-

terfere with the proper assembly and operation of the device. Without intending to limit myself to the use of these exact dimensions, I have found that stock twenty thousandths of an inch thick 5 and one hundred and forty thousandths wide is admirably adapted for the purpose.

It will be understood that in the manufacture of the pivot pin and in the forming of the grooves 26 certain tolerances in dimensions are necessary; 10 and within such dimensional limits a space between the end parts of the pivot pin and the bottoms of the grooves may occur as indicated at 37. To avoid any possibility of the ends of the retainer 27 slipping into this aforementioned 15 space they are turned inward to form offset abutments or bearing portions as indicated at 38. This serves the double purpose of insuring correct location of the parts, and also presenting sufficient bearing area between the pin and the 20 retainer to avoid excessive wear at that point.

Referring to Figure 5 of the drawing, it will be noted that grooves 26 are partially closed at their lower ends by projecting metal 39 which provides separating walls between the ends 38 25 of retainer 27 and bearings 40 of the float lever 24 and also provides guides for the more exact location of pin 25 which is considerably smaller in diameter than the width of grooves 26.

For normal and high speed engine operation, 30 fuel is admitted to the mixing conduit thru nozzle 29 and discharged thru openings 30 in jet bar 31. For low speed operation fuel is admitted to ports 32 thru low speed passages 33, 34, and 35.

35 In operation air enters the mixing conduit thru inlet 4 and passes thru restriction 5 aspirating fuel from the jet 30 and low speed ports 32 according to the position of the throttle and the operating conditions of the engine in a manner 40 well understood in the art.

The float, float lever 24, pin 25 and retainer 45 may readily be removed or replaced upon removal of screws 3 and the combined air horn and float chamber cover 2. When the parts are in position as shown in Figure 1, the member 27 is slightly compressed between the cover 2 and the pin 25, so as to hold the pin firmly in position without interfering with its turning movement, so that the pin may be rotated with respect to 50 either the float lever bearing 40 or the groove 26, or both.

The invention is not limited to the structure shown but may be modified in various respects as will occur to those skilled in the art and the 55 exclusive use of all such modifications as come within the scope of the appended claims is contemplated.

I claim:

1. In a carburetor having a float chamber, float 60 mechanism therein, and pivotal support means for said mechanism, said means comprising a pair of spaced grooves formed in the walls of said float chamber, pin parts on said float mechanism engaging and supported in said grooves, and a 65 separate retaining structure in said grooves engaging said pin parts for retaining said parts in position in said grooves.

2. A constant level fuel chamber, having a pivoted float mechanism, a pivot pin for said float 70 mechanism, a recess in one side of said constant level chamber, a threaded opening in the end wall of said recess for receiving a fuel inlet member, a pair of parallel vertical grooves in the side walls of said recess, the lower ends of said grooves 75 forming bearings for said pivot pin, and sep-

arate means for retaining said pivot pin at the lower ends of the said grooves.

3. In a carburetor, a float chamber having a cover member and parts with opposing vertical 5 grooves and float support mechanism comprising a float pivot pin having an end supported in and engaging each of said grooves and a retainer for said pivot pin comprising a substantially U-shape, flexible sheet metal member, said cover member being constructed and arranged when 10 applied to said chamber to contact the upper part of said retainer and thereby hold said float pivot pin in place.

4. Carburetor fuel chamber structure comprising a part having a groove, float pivot means extending into said groove and supported therein, and a retainer in said groove separate from said pivot means for resisting movement of said means longitudinally of said groove.

5. Structure as specified in claim 4 in which 20 said retainer is in the form of a thin sheet metal spring disposed at least in part longitudinally within said groove and having an offset abutment at one end for engaging said pivot means and resisting movement thereof longitudi- 25 nally of said groove.

6. Carburetor fuel chamber structure comprising parts having opposing grooves, float pivot means supported in said grooves, and a retainer for said pivot means comprising a U-shaped resilient strip with its ends frictionally engaging the walls of said grooves and engaging said means.

7. Structure as specified in claim 6 in which said U-shaped retainer strip has bent elements at the ends of its leg portions for engaging said 35 pivot means.

8. In a carburetor having a constant level fuel chamber, a recess in one side of said chamber forming a fuel inlet and having side structure, and grooves in said side structure for receiving 40 float pivot means, said structure including elements extending partly across the open sides of said grooves at the lower portions thereof and forming float pivot bearing structure.

9. Constant level chamber structure comprising 45 a part having a groove, float pivot means in said groove, and a pivot retainer also in said groove, said retainer being wider than said pivot means and said part having an element extending partially across said groove and forming a 50 restricted bearing portion therein for said pivot means.

10. Structure as specified in claim 9 in which 55 said element extends across a portion of said retainer.

11. Constant level chamber structure comprising a part having a groove, a float pivot supported in said groove, and a retainer in said groove engaging said pivot, said groove being restricted adjacent said pivot to form a snug bearing portion therefor.

12. In a carburetor, a constant level fuel chamber, a cover for said fuel chamber, float mechanism in said chamber, and pivotal support means for said float mechanism comprising a pair of 65 grooves in spaced portions of said fuel chamber, float pivot parts engaging said grooves, and separate retainer structure in said grooves and engaging said parts, said structure being frictionally maintained in position by its inherent resiliency and said cover engaging said structure to additionally maintain said structure and said pivot parts in position.
